(57) **CLAIM**

I claim the ornamental design for a sofa, as shown and described.

DESCRIPTION

FIG. 1 is a perspective view of a sofa according to a first embodiment of my new design.

FIG. 2 is a front view of the sofa of FIG. 1.

FIG. 3 is a rear view of the sofa of FIG. 1.

FIG. 4 is a first side view of the sofa of FIG. 1.

FIG. 5 is a second side view of the sofa of FIG. 1.

FIG. 6 is a top view of the sofa of FIG. 1.

FIG. 7 is a bottom view of the sofa of FIG. 1.

FIG. 8 is a perspective of a sofa according to a second embodiment of my new design.

FIG. 9 is a front view of the sofa of FIG. 8.

FIG. 10 is a rear view of the sofa of FIG. 8.

FIG. 11 is a first side view of the sofa of FIG. 8.

FIG. 12 is a second side view of the sofa of FIG. 8.

FIG. 13 is a top view of the sofa of FIG. 8.

FIG. 14 is a bottom view of the sofa of FIG. 8.

FIG. 15 is a perspective of a sofa according to a third embodiment of my new design.

FIG. 16 is a front view of the sofa of FIG. 15.

FIG. 17 is a rear view of the sofa of FIG. 15.

FIG. 18 is a first side view of the sofa of FIG. 15.

FIG. 19 is a second side view of the sofa of FIG. 15.

FIG. 20 is a top view of the sofa of FIG. 15.

FIG. 21 is a bottom view of the sofa of FIG. 15.

FIG. 22 is a perspective of a sofa according to a fourth embodiment of my new design.

FIG. 23 is a front view of the sofa of FIG. 22.

FIG. 24 is a rear view of the sofa of FIG. 22.

FIG. 25 is a first side view of the sofa of FIG. 22.

FIG. 26 is a second side view of the sofa of FIG. 22.

FIG. 27 is a top view of the sofa of FIG. 22; and,

FIG. 28 is a bottom view of the sofa of FIG. 22.

(Continued)

The broken lines in the figures are for the purpose of illustrating portions of the sofa, which form no part of the claimed design.

1 Claim, 24 Drawing Sheets
